2 SHEETS—SHEET 2.

UNITED STATES PATENT OFFICE.

JOHN J. B. ARTER, OF GREET, NEAR BIRMINGHAM, ENGLAND.

MACHINE, ANTI-AIRCRAFT, AND OTHER GUN.

1,334,983.

Specification of Letters Patent. Patented Mar. 30, 1920.

Application filed July 8, 1918. Serial No. 243,862.

To all whom it may concern:

Be it known that I, JOHN JAMES BEDNEY ARTER, a subject of the King of Great Britain, residing at James Works, Greet, near 5 Birmingham, in the county of Warwick, England, have invented a new and useful Improvement in Machine, Anti-Aircraft, and other Guns; and I do hereby declare the following to be a full, clear, and exact description of the same.

My invention comprises improvements in machine, anti-aircraft, and other guns and refers more particularly to that class of gun which embodies a plurality of relatively divergent barrels adapted to be fired simultaneously; the object of the present invention being to provide an improved gun which may be constructed in a light form as a machine gun for use upon aircraft, or may 15 be constructed in a heavier form for use as an anti-aircraft gun and firing a larger projectile.

According to this invention the gun embodies a plurality of barrels in combination 20 with means for varying the angle of divergence and also means for simultaneously charging all the barrels and means for simultaneously firing them.

A gun according to this invention broadly 25 comprises a plurality of barrels, means for varying the angle of divergence, a magazine container at the rear end of the barrels, firing mechanism, a stand, and a universal joint for supporting the gun upon the stand.

30 In the accompanying drawings:—

Figure 1 is a view in side elevation of a gun constructed according to my invention.

Fig. 2 is an end view partly in section.

Fig. 3 is a view partly in section and upon 35 an enlarged scale showing a detail of the gun mounting.

Fig. 4 is a view in sectional side elevation upon an enlarged scale showing the firing mechanism and the means for varying the 40 angle of divergence of the barrels.

Fig. 5 is a fragmentary view in section showing the means for withdrawing the cartridge after firing.

The barrels 1 are formed with spherical 45 rear extremities 2 which fit within corresponding recesses 3 in a plate 4 attached to the breech body 5 and held in position by a

retaining ring 6 again having a similar recess.

The angle of divergence of the barrels 1 is 55 controlled by a sliding member 7 engaged by a central screw 8 on a rod 17 which is actuated by a pair of bevel wheels 9, 10 and graduated hand wheel 11, this sliding member 7 being connected to the barrels 1 by 60 links 12 again preferably having spherical extremities 13 which engage with a corresponding recess in the slide 7 and being held by a suitable retaining ring 14. Each link 12 is pivotally connected at 15 to a collar 16 65 on a barrel 1.

The rod 17 is supported at one end in a bush 18 carried by the plate 4 and another point of support is provided by a boss 19 upon the member 20 which is attached to the 70 ring 6.

The member 20 is provided with radial arms 21, one for each barrel and at their outer ends these arms 21 are slotted at 22, which slots form radial guides for the barrels. 75

The barrels 1 are arranged in a circle and means are provided for simultaneously charging them, such means comprising a clip ring 23 (see Figs. 4 and 5) adapted to carry 80 cartridges corresponding in number with the barrels of the gun, this ring 23 being inserted into the breech body 5 through a suitable opening formed by removal of the plate 24, the whole of the cartridges 25 being 85 pressed home into the barrel chambers while still remaining in position in the clip 23. While, after firing, the clip 23 and cartridges 25 are withdrawn and may be arranged to fall out at the bottom of the breech body, or 90 they may be lifted out at the top.

The firing mechanism broadly comprises a ring or disk 26 carrying a series of firing pins 27, one for each cartridge, together 95 with a striker 28 which simultaneously engages all the firing pins 27, the ring or disk 26 also carrying means for gripping the clip 23 and thus withdrawing the cartridges 25.

The ring 26 contains a series of hammers 100 29 spring receded by springs 30 and corresponding in position with the gun barrels 1, the ring 26 being carried by a sliding shaft 31 the rear end of which is externally

screwed at 32 and engages with a nut 33 held against axial movement and carrying bevel gear teeth 34 which are engaged by similar teeth 35 on a short shaft controlled 5 by a hand wheel 36, so arranged that rotation of the hand wheel in the one direction will press the cartridges into position in the barrel chambers at the same time putting the hammers into position for firing, while 10 rotation in the opposite direction will withdraw the cartridges, automatically releasing them and permitting others to be inserted in their place.

The means for withdrawing the cartridges 15 comprises a plurality of fingers 37 pivoted at 38 upon the periphery of the ring 26 and having hooked extremities 39 which engage with the outer periphery of the ring 23 which forms the clip for carrying the cartridges. These hooked fingers 37 are pressed outwardly by springs 40 against the interior wall of the breech body 5, this interior being, however, of two diameters, the diameter at the rear 5^a being greater than at the forward end 5^b so that when the hammer ring 26 is retracted to the rear end of the breech body the fingers 37 will move outwardly and release the cartridge clip 23, while when the ring 26 is moved forwardly the fingers 37 20 are pressed inwardly and will grip the clip 23 if the clip has been inserted in a suitable position. The clip 23 is thus moved forwardly so as to bring the cartridges into place simultaneously with the hammer ring 26, while, after firing, the return movement of the ring 26 takes with it the clip 23 and cartridges 25 which are released when they have reached a position where the large diameter 5^a permits the fingers 37 to open.

40 The striker comprises a disk 28 which is adapted to simultaneously engage with the whole of the hammers 29. This striker disk 28 is carried by a hollow shaft 41 disposed around the shaft 31 which carries the hammer ring, and when released the striker 28 is advanced by a strong spring 42 so as to simultaneously strike the whole of the hammers 29. The striker 28 is normally held in its receded position by a projection 43 which 45 engages with a spring trigger 44, the release of which serves to release the striker. After firing, the striker 28 is receded with the hammer ring 26, being automatically locked in its receded position when it engages with the trigger 44.

55 The gun is preferably mounted so as to be capable of angular movement both in horizontal and vertical planes. The breech body 5 is provided with a downwardly projecting spigot portion 45 which engages with a corresponding socket 46 in a member which is held against movement in a horizontal plane, being locked by a cam 47 controlled by a suitable lever 48.

65 This socket member 46 is also provided

with a horizontal spigot portion or shaft 49 which is screwed at 50 and carries a hand wheel 51, rotation of which releases a locking clutch 52 and permits the gun to be moved angularly about a horizontal axis. 70 The socket member 46 has an externally tapered socket member 52 which engages with a correspondingly internally tapered part 53 of the gun stand, a suitable spring 54 being disposed between these two parts 75 which disengages them when the hand wheel is suitably rotated.

What I claim then is:—

1. A gun, comprising in combination a plurality of circularly-disposed barrels each 80 having a fixed collar thereon; means for varying the angle of divergence of each barrel including a rotatable screw-threaded rod projecting between and concentrically disposed relatively to the barrels; means for 85 rotating said rod; a screw-threaded block mounted upon said rod; radially-disposed links, each of said links having one end pivoted on said block and having the other end pivotally secured to one of the fixed collars; 90 a magazine container at the rear end of the barrels; firing mechanism; a stand; and a universal joint for supporting the gun upon the stand.

2. A gun, comprising in combination a 95 plurality of circularly-disposed barrels each having a fixed collar thereon; means for varying the angle of divergence of each barrel including a rotatable screw-threaded rod projecting between and concentrically disposed relatively to the barrels; means for 100 rotating said rod, comprising a pair of bevel wheels and a graduated hand wheel for operating them; a screw-threaded block mounted upon said rod; radially-disposed links, each of said links having one end pivoted on said block and having the other end pivotally secured to one of the fixed collars; 105 a magazine container at the rear end of the barrels; firing mechanism; a stand; and a universal joint for supporting the gun upon the stand.

3. A gun comprising in combination a plurality of circularly disposed barrels; means for varying the angle of divergence of each barrel including a rotatable screw-threaded rod projecting between and concentrically disposed relatively to the barrels; means for rotating said rod; a screw-threaded block mounted upon said rod; radially-disposed links each pivoted at one end to said block and at the other end pivotally secured to one of the fixed collars; a magazine container at the rear end of the barrels; 115 firing mechanism; means for withdrawing cartridges from the barrels; a stand; and a universal joint for supporting the gun upon the stand.

4. A gun comprising in combination a

plurality of circularly disposed barrels; means for varying the angle of divergence of each barrel including a rotatable screw-threaded rod projecting between and concentrically disposed relatively to the barrels; means for rotating said rod; a screw-threaded block mounted upon said rod; radially-disposed links each pivoted at one end to said block and at the other end pivotally secured to one of the fixed collars; a magazine container at the rear end of the barrels; firing mechanism including a disk having a number of recesses equal to the number of barrels and similarly spaced; each recess containing a spring pressed firing pin; means for moving said disk up to or away from the rear ends of the barrels; means for operating the firing pins; a stand; and a universal joint for supporting the gun upon the stand.

5. A gun comprising in combination a plurality of circularly disposed barrels; means for varying the angle of divergence of each barrel including a rotatable screw-threaded rod projecting between and concentrically disposed relatively to the barrels; means for rotating said rod; a screw-threaded block mounted upon said rod; radially-disposed links each pivoted at one end to said block and at the other end pivotally secured to one of the fixed collars; a magazine container at the rear end of the barrels; firing mechanism including a disk having a number of recesses equal to the number of barrels and similarly spaced; each recess containing a spring pressed firing pin; means for moving said disk up to or away from the rear ends of the barrels; means for operating the firing pins; means for withdrawing cartridges from the barrels; a stand; and a universal joint for supporting the gun upon the stand.

6. A gun comprising in combination a plurality of barrels; means for varying the angle of divergence; a magazine container at the rear end of the barrels; firing mechanism including a disk having a number of recesses equal to the number of barrels and similarly spaced; each recess containing a spring pressed firing pin; means for moving said disk up to or away from the rear ends of the barrels; means for operating the firing pins; means for withdrawing cartridges from the barrels including a plurality of spring pressed extracting fingers pivoted to said disk and contacting with the interior wall of a breech chamber surrounding said disk; said wall having two portions of different diameters allowing said extracting fingers to move outwardly when the disk is moved back from the barrels; a stand; and a universal joint for supporting the gun upon the stand.

7. A gun comprising in combination a plurality of barrels; means for varying the

angle of divergence including a member between the barrels; means for moving same parallel to the barrels; links connecting each barrel to said member; a magazine container at the rear end of the barrels; firing mechanism including a disk having a number of recesses equal to the number of barrels and similarly spaced; each recess containing a spring pressed firing pin; means for moving said disk up to or away from the rear ends of the barrels; means for operating the firing pins; means for withdrawing cartridges from the barrels including a plurality of spring pressed extracting fingers pivoted to said disk and contacting with the interior wall of a breech chamber surrounding said disk; said wall having two portions of different diameters allowing said extracting fingers to move outwardly when the disk is moved back from the barrels; a stand; and a universal joint for supporting the gun upon the stand.

8. A gun, comprising in combination a plurality of circularly-disposed barrels pivotally mounted in the breech chamber, each barrel having a fixed collar thereon; radial guides for said barrels; means for varying the angle of divergence of each barrel, including a rotatable screw-threaded rod projecting between and concentrically disposed relative to the barrels; means for rotating said rod; a screw-threaded block mounted upon the rod; radially-disposed links each pivoted at one end to said block and having the other end pivotally secured to one of the fixed collars on said barrels; a magazine container at the rear end of the barrels; firing mechanism; a stand; and a universal joint for supporting the gun upon the stand.

9. A gun comprising in combination a plurality of circularly disposed barrels; means for varying the angle of divergence of each barrel including a member between the barrels; means for moving same parallel to the barrels; links connecting each barrel to said member; a magazine container at the rear end of the barrels; firing mechanism including a disk having a number of recesses equal to the number of barrels and similarly spaced; each recess containing a spring pressed firing pin; means for moving said disk up to or away from the rear ends of the barrels; means for operating the firing pins including a striker consisting of a disk having a rearward sleeve-like extension; a projection on said extension; a trigger engaging said projection; a spring to move the striker into contact with the firing pins when the trigger is released from said projection; a stand; and a universal joint for supporting the gun upon the stand.

10. A gun comprising in combination a plurality of barrels; means for varying the angle of divergence; a magazine container at the rear end of the barrels; firing mecha-

nism including a disk having a number of recesses equal to the number of barrels and similarly spaced; each recess containing a spring pressed firing pin; means for moving said disk up to or away from the rear ends of the barrels including a screw threaded rod working in a stationary nut; a hand

wheel for rotating said rod; means for operating the firing pins; a stand; and a universal joint for supporting the gun upon the stand. 10

In testimony whereof, I have signed my name to this specification.

JOHN J. B. ARTER.
